UNITED STATES PATENT OFFICE.

FREDERICK W. HORSTMANN, OF IRVINGTON, NEW JERSEY.

FUR-TRIMMING MACHINE.

Application filed July 9, 1925. Serial No. 42,368.

This invention relates to fur-shearing machines and more particularly to an improvement in such machines whereby the fur may be more uniformly sheared or trimmed 5 without requiring any unusual skill on the part of the operator.

Fur-shearing machines as at present designed are not entirely satisfactory in that it is not possible to shear the fur uniformly 10 without unusual care or skill on the part of the operator. In such machines it is the practise for the operator to maintain the skin taut while being drawn and passed over the stretcher bar or apron. Obviously 15 due to the personal factor the degree of tension applied to the skin while it is thus disposed may vary within wide limits. This results in a non-uniform shearing of the skin. Another disadvantage of the present 20 types of fur-trimming machines is that they are not designed to permit one to quickly bring a fur or skin into cutting position without endangering the operator's fingers.

The present invention overcomes the foregoing disadvantages by providing mechanism for such machines which maintains the skin in close contact with the stretcher bar and at the same time applies a uniform tension thereon, whereby it is possible to 25 consistently obtain uniform shearing of the fur without any special reliance being placed upon the operator. In addition, the present invention also provides mechanism for permitting the positioning of the fur about the 30 stretcher bar and for holding the same in firm contact therewith while the skin is being brought into position adjacent the cutting knives, this being accomplished without the necessity of the operator bringing 35 his or her fingers into close proximity to the cutters.

Another disadvantage of fur-shearing machines as at present employed is their limitation to handling skins or strips of fur of 40 considerable width without requiring several passes through the mechanism. This disadvantage is overcome in the machine forming the subject of my invention by providing a combination of elements including 45 a smoother bar which continuously stretches the skin toward the outer longitudinal edges thereof as the skin is being drawn over the stretcher bar by an operator.

In view of the foregoing, it is an object

of my invention to provide a fur-shearing 55 machine which is adapted to cut the fur a uniform depth over substantially its entire surface without requiring any unusual skill on the part of the operator.

Another object of the invention is to provide a fur-shearing machine which is adapted 60 to permit the presentation of a skin to the shearing knives without endangering the operator's fingers.

Another object of the invention is to provide a fur-shearing machine which is adapted 65 for trimming or shearing fur of any width in a uniform manner without the necessity of passing the fur several times 70 through the mechanism.

A more specific object of the invention is to provide a fur-trimming machine in which is embodied a tension device for firmly securing the skin in position about the 75 stretcher bar or apron.

Another specific object of my invention is to provide a fur-shearing machine which is adapted to smooth the skin toward its edges 80 thus enabling skins of greater width to be accommodated by the machine.

Other objects of the invention will be apparent as the following detailed description is read.

The invention will be more fully understood by reference to the accompanying 85 drawing in which

Fig. 1 is a side elevational view of a fur-shearing machine embodying the features of my invention.

Fig. 2 is a front elevational view of the 90 machine illustrated in Fig. 1; and

Fig. 3 is a fragmentary plan view illustrating the device for smoothing the fur toward its edges to adapt the machine for handling furs of larger sizes.

Referring to the drawings, wherein like reference characters designate corresponding parts throughout the several views, 95 designates a frame or stand which supports a motor 6 for driving the customary cylinder 100 knives 7 by means of an endless belt 8. The cylinder knives are enclosed within a housing or casing 9 open at its front and having a rear opening 10 for connection to an exhaust fan or blower, not shown, whereby the 105 hair of the fur may be withdrawn. A bracket 11 supports the usual bed knife 12 by suitable bolts or other fastening means,

said bed knife cooperating with the cylinder knives to sever and cut the hair of the skin 13 as the latter is drawn past the knives.

The frame or stand 5 supports a horizontal shaft 14 upon which is mounted vertical side members 15 which may swing relative to the frame 5 when urged forwardly by a buffer 16 which is disposed parallel to the shaft 14 and is secured to the side members 15. A pair of slotted bars 17 pivoted to the front of the frame 5 are provided with slots 18 for the passage of a pin 19 extending from each of the members 15. In addition an adjustable stop 20 limits the inward movement of the frame or members 15 that support the apron or stretcher bar referred to more fully hereinafter.

The upper ends of the vertical members 15 are slotted and slidably support vertically adjustable arms 21 which are substantially L-shaped. The arms may be secured in any desired position of adjustment by bolts 22. The outer ends of the arms 21 support a stretcher bar or roller 23 which is journaled in suitable bearings in said arms. The roller is of relatively small diameter, so that as the skin or fur is passed or pulled over the surface of said roller the hair will be presented to the cutting action of the knives so that an even, regular and close cut may be obtained.

The foregoing structure is well known in the art and therefore requires no more detailed description. As pointed out heretofore machines of this type are not entirely satisfactory inasmuch as no mechanical means are provided for maintaining the skin taut during the shearing operation, dependency being placed entirely upon the operator for securing this result. In addition, such machines required the operator to hold the skin on the stretcher bar while it is being brought to position adjacent the cutters. Obviously, since it is desired to shear as much of the skin as is possible, the edge of the skin must be held by the operator as closely as possible to the edge of the stretcher bar. Unless considerable skill and care is exercised on the part of the operator considerable danger is attendant this operation even though guard rails or bars have been provided for such machines. Furthermore, with the former machines unless the operator pays close attention to the work the cutting of the fur is not uniform by reason of the fact that the skin is not maintained uniformly taut or fed to the cutters at the same angle.

In order to overcome the foregoing disadvantages I have provided what may be termed a tensioning device which maintains the skin or fur taut and free from slippage during the shearing or cutting operation and presents the fur at the same angle to the shearing mechanism. At the same time

the tensioning device permits the skin to be brought adjacent the cutters without the operator's hand coming into close proximity to the cutters. Where the skin or fur is irregular or thicker in one place than in another, it is necessary that the tensioning means shall conform to such irregularities without hindering or impeding the progress of the skin as it is being drawn over the stretcher bar or roller 23. Means are provided in the tensioning device forming the subject of my invention for attaining this end.

The tensioning device comprises pairs of top and bottom levers 25 and 26 pivoted at 27 and 28, respectively, in the brackets 29, which latter are supported on the top of the frame or stand 5. The levers 25 are bent downwardly as at 30 and journaled in the ends thereof is a suitable roller 31 of very small diameter. The levers 26 are bent upwardly as at 31^a and also journaled in the ends thereof is a suitable small roller 32. The rollers 31 and 32 bear on the top and bottom, respectively, of a skin and against the upper and lower surfaces of a smoother bar 36, thus firmly holding the skin in position as it is advanced toward and drawn past the shearing or cutting mechanism. The outer ends of the levers 25 and 26 are provided with openings through which loosely pass threaded bolts 33 on which tension springs 34 are mounted, which springs maintain the rollers 31 and 32 in engagement with the skin on the apron. The rollers 31 and 32 may be adjusted toward and from each other by nuts 34' which engage the threaded ends of the bolts 33, thus permitting the space between the rollers to be adjusted to accommodate different size stretcher bars 23 and different thicknesses of skins, and also permitting regulation of the degree of tension applied by the rollers 31 and 32 upon a skin. It is also apparent that the rollers 31 and 32 may be maintained a fixed distance apart by reason of the foregoing construction.

To regulate the depth of cut I provide auxiliary threaded bolts 35 projecting upwardly from extensions 37 secured to the brackets 29. The extensions rigidly carry the bolts 35 and the latter pass loosely through apertures in the arms 25, springs 36' being interposed between the extensions 33 and the levers 25 so that by adjusting the nuts 38 said levers as well as the rollers 31 and 32 secured thereto may be rocked on their pivots so that the rollers may be simultaneously moved substantially vertically with respect to the stretcher bar 23. The brackets 29 may be horizontally adjusted with respect to the stretcher bar by reason of bolts 29' tapped into the top of the frame, said bolts passing through slots 29" in the brackets 29. By loosening up the bolts the bracket

ets as well as the mechanism supported thereby may be shifted horizontally and by turning down upon the bolts 29' the brackets may be maintained securely in any desired 5 position of adjustment. By reason of the foregoing adjustments, it is possible to so adjust the tensioning device with respect to the cutters so as to obtain any desired cut and at the same time proper compensation 10 may be made for any wear that may take place in the cutting knives.

In view of the tensioning means or coil springs 34 being mounted between the ends 15 of the levers 25 and 26, when the stretcher bar roller 23 is moved to its extreme outer position, the rollers 31 and 32 will move relative to each other as the bar passes therebetween. As the buffer 16 is engaged and moves the stretcher bar 23 inwardly after 20 a skin has been draped around the same the skin will be engaged by the rollers 31 and 32 with considerable tension to firmly hold the skin in position about the stretcher bar as it is brought adjacent the cutters and 25 while the skin is being advanced past the same. The diameter of the rollers 31 and 32 and their relation to the roller 23 is such that the same angular relation of the hairs of the skin is maintained whereby an even, 30 regular and uniform cut is affected to produce the required work.

In order that skins of considerable width may be sheared without the necessity of passing the skins several times through the 25 machine, I have provided what may be termed a smoother bar 36. Referring to Fig. 3, this bar comprises a flat body portion having a wedge-shaped edge 40. The bar is positioned between the arms 21 and 30 firmly bolted thereto. The location of the bar with respect to the stretcher roller 23 is such that when a skin is brought into close proximity to the cutters the longer end of the skin will hang over the wedge-shaped 35 edge 40 of the smoother bar. As the operator takes hold of the lower or shorter end of the skin with his hands and draws the skin past the cutters, the skin is stretched over the wedge-shaped edge of the smoother 40 bar by reason of its own weight. The resultant action upon the skin is to smooth the skin outwardly from its median line toward its edges. Obviously, in view of the presence of the smoother bar it is possible 45 to handle skins of larger widths without the necessity of several passes through the cutting mechanism to shear the same over its entire surface.

It is also apparent that by reason of the 50 provision of tension rollers that it is possible to handle skins of greater width than heretofore, this being made possible by the smoothing action of the tension rollers upon the skins over their entire widths as well as 55 permitting the operator to engage the lower

end of the skin with both hands and exert the necessary side force to maintain the skin smooth as well as to apply a uniform force to move the same past the cutters.

While I have illustrated and described my 70 invention with some degree of particularity, I realize that in practise various alterations therein may be made. I therefore reserve the right and privilege of changing the form of the details of construction or otherwise 75 altering the arrangement of the correlated parts without departing from the spirit of the invention or the scope of the appended claims:

Having thus described my invention, what 80 I claim as new and desire to secure by United States Letters Patent, is:

1. A fur-trimming machine comprising means for trimming fur, a stretcher bar adapted to be moved toward and from said trimming means, and means for engaging a skin draped over said stretcher bar to maintain the skin in firm contact therewith. 85

2. A fur-trimming machine comprising means for trimming the fur, a stretcher bar adapted to be moved toward and from said trimming means, and means for engaging the fur side of a skin when draped over said stretcher bar to maintain the skin in firm 90 contact therewith. 95

3. A fur-trimming machine comprising means for trimming fur, a stretcher bar adapted to be moved toward and from said trimming means, and a tensioning device co-operating with said stretcher bar for maintaining a skin taut as it is moved in proximity to said trimming means. 100

4. A fur-trimming machine comprising cutting mechanism, a swinging frame and an apron or stretcher bar carried thereby, and tensioning means above and below said bar for maintaining a skin taut as it is moved in proximity to said cutting mechanism and as it is drawn over said bar. 105

5. A fur-trimming machine comprising cutting mechanism, a swinging frame and an apron or stretcher bar carried thereby, and tensioning means cooperating with said bar at a point rearwardly of its working edge for maintaining a skin taut as it is moved in proximity to said cutting mechanism. 110

6. A fur-trimming machine comprising cutting mechanism, a swinging frame and an apron or stretcher bar carried thereby 115 consisting of a roller, and adjustable tensioning means cooperating with said roller at a point rearwardly of its working edge for maintaining a skin taut as it is moved over said stretcher bar. 120

7. In combination with the cutting mechanism of a fur-trimming machine, a swinging frame and an apron or stretcher bar carried thereby, adjustable tensioning rollers above and below said bar, said frame being mov- 130

able toward and from said cutting mechanism, said stretcher bar being adapted to pass between the adjustable tensioning rollers to maintain a skin taut as it is moved in proximity to said cutting mechanism.

8. In combination with the cutting mechanism of a fur-trimming machine, a swinging frame, a plurality of adjustable supporting arms and an apron or stretcher bar carried thereby, a pair of tensioning levers having rollers adapted to engage the top and bottom and rearwardly of the working edge of said stretcher bar, and means for actuating the frame whereby the tensioning rollers are separated to engage a skin on said stretcher bar and maintain it taut as it is advanced in proximity to the cutting mechanism.

9. A fur-trimming machine comprising a support, cutting mechanism and a swinging frame carried by said support, a stretcher bar at the upper end of said frame, a pair of tensioning levers pivoted on said support, rollers on the inner ends of said levers above and below said stretcher bar, and resilient means between said levers, whereby they may be spread and the rollers carried thereby engage said stretcher bar to maintain a skin taut as it is advanced in proximity to the cutting mechanism.

10. A fur-trimming machine comprising a support, cutting mechanism, and a swinging frame carried by said support, means for adjustably supporting a stretcher bar at the upper end of said frame, a stretcher bar supported by said means levers pivotally mounted on said support, tensioning rollers on the ends of said levers above and below said stretcher bar, resilient means for said levers whereby they may be moved relative to each other, and means for adjusting said levers as a unit vertically with respect to said stretcher bar.

11. A fur-trimming machine comprising a support, cutting mechanism and a swinging frame carried by said support, a stretcher bar at the upper end of said frame, a pair of tensioning levers pivoted on the support, rollers on the inner ends of said levers above and below said stretcher bar, resilient means between said levers, and means for adjusting said rollers toward and from each other.

12. A fur-trimming machine comprising a support, cutting mechanism and a swinging frame carried by said support, a stretcher bar at the upper end of said frame, a pair of tensioning levers pivoted on the support, rollers on the inner ends of said levers above

and below said stretcher bar, and means for adjusting said rollers as a unit horizontally with respect to said stretcher bar.

13. A fur-trimming machine comprising a support, cutting mechanism and a swinging frame carried by said support, means for adjustably supporting a stretcher bar or apron at the upper end of said frame, a stretcher bar supported by said means levers pivotally mounted on said support, tensioning rollers on the ends of said levers above and below said stretcher bar, resilient means for said levers whereby they may be moved relative to each other, and means for adjusting said rollers with respect to each other and vertically and horizontally with respect to said stretcher bar.

14. A fur-trimming machine comprising means for trimming the fur, a stretcher bar adapted to be moved toward and from said trimming means, and means for engaging a skin as it is moved toward said trimming means to securely hold the skin in position about said stretcher bar as the latter is brought into close proximity to said trimming means without the necessity of the operator holding the skin about said stretcher bar, whereby danger to the operator is avoided.

15. A fur-trimming machine comprising means for trimming the fur, a stretcher bar adapted to be moved toward and from said trimming means, and means for smoothing a skin towards its edges as the skin is drawn over said stretcher bar.

16. A fur-trimming machine comprising means for trimming the fur, a stretcher bar, means cooperating with said stretcher bar for maintaining a skin taut about said stretcher bar, and means for smoothing a skin toward its longitudinal edges as the skin is drawn over said stretcher bar.

17. A fur-trimming machine comprising a support, cutting mechanism and a swinging frame carried thereby, a stretcher bar mounted upon said frame, a smoother bar also mounted upon said frame and disposed adjacent said stretcher bar, and means for applying tension to a skin disposed about said stretcher bar and having its longer end hanging over said smoother bar, whereby a skin may be maintained taut over said stretcher bar and smoothed toward its edges as it is drawn over said bar.

In testimony whereof I affix my signature.

FREDERICK W. HORSTMANN.
